Filed Mar. 7, 1974, Ser. No. 449,059

Term of patent 14 years

Int. Cl. D20—03

U.S. Cl. D96—12 R

FIG. 1 is a front perspective view of a carousel advertising display sign for stores embodying my new design; FIG. 2 is a side elevational view thereof;

FIG. 3 is a bottom plan view thereof; and

FIG. 4 is a fragmentary side elevational view of a second embodiment of my design, the upper portion which is fragmentarily shown for convenience of illustration, is identical to the upper portion of the first embodiment. The supporting member includes three downwardly biased support legs extending radially outwardly from the center pole to define a tripod.

The indicia and shelf are shown in broken lines for illustrative purposes only.

I claim:

The ornamental design for a carousel advertising display for stores, substantially as shown and described.
